US0D1095561S

(12) **United States Design Patent** (10) **Patent No.:** **US D1,095,561 S**
(45) **Date of Patent:** **** Sep. 30, 2025**

(54) **DISPLAY SCREEN OR PORTION THEREOF WITH GRAPHICAL USER INTERFACE**

(71) Applicant: **Sungrow Icarbon Technology Co., Ltd.**, Anhui (CN)

(72) Inventors: **Lian Ma**, Hefei (CN); **Xuhan Huang**, Hefei (CN)

(73) Assignee: **Sungrow Icarbon Technology Co., Ltd.**, Anhui (CN)

(**) Term: **15 Years**

(21) Appl. No.: **29/917,912**

(22) Filed: **Nov. 22, 2023**

(30) **Foreign Application Priority Data**

May 23, 2023 (CN) 202330306437.8

(57) **CLAIM**

The ornamental design for a display screen or portion thereof with graphical user interface as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface according to a first embodiment of the present application; and,

FIG. 2 is a front view of a display screen or portion thereof with graphical user interface according to a second embodiment.

The outermost broken lines in the figures show a display screen or portion thereof and form no part of the claimed design. The other broken lines in the figures show text, letter and number content of the graphical user interface that form no part of the claimed design.

1 Claim, 2 Drawing Sheets
(2 of 2 Drawing Sheet(s) Filed in Color)
